Attorney.

UNITED STATES PATENT OFFICE

1,997,560

LOOM REED

John Jacob Kaufmann, Elkins Park, Pa., assignor
to Steel Heddle Manufacturing Company,
Philadelphia, Pa., a corporation of Pennsyl-
vania

Application December 15, 1933, Serial No. 702,441

11 Claims. (Cl. 139—192)

My invention relates to improvements in loom reeds, and more especially to a loom reed of the soldered type in which a novel mounting is provided for the dents.

5 In the use of reeds of the conventional soldered type construction, difficulty is encountered because of the premature failure of the dents. The hard metal of the dents is in contact with the hard metal of the spring, and the strains 10 set up in this portion of the dent materially shorten the useful life of the reed. Vibrations may be set up in the reed during use, which contribute to fatigue of the dent metal at or near the place of contact.

15 One of the principal objects of my invention is to provide a loom reed construction which will have a long life and will withstand rough treatment.

20 A further object of my invention is to provide a reed which will not be weakened by vibration of the dents.

Another object of my invention is to provide a loom reed which will be light in weight but at the same time durable and sturdy.

25 The nature and characteristic features of my invention will be more readily understood from the following description, taken in connection with the accompanying drawing forming part hereof, in which:

30 Figure 1 is a front elevational view of a portion of a reed embodying my invention;

Fig. 2 is a sectional view taken on the line 2—2 of Fig. 1, and shows the solder as applied to one of the dents;

35 Fig. 3 is a front elevation of a portion of a modified form of reed embodying the main features of my present invention, the upper left hand portion being broken away to show the details of construction adjacent the ends of the dents;

40 Fig. 4 is a sectional view taken on the line 4—4 of Fig. 3 and shows the solder as applied to one of the dents.

Fig. 5 is an enlarged fragmentary view of the 45 form of reed shown in Fig. 1;

Fig. 6 is a side sectional view taken on the line 6—6 of Fig. 5;

Fig. 7 is an enlarged fragmentary view of the form of reed shown in Fig. 2;

50 Fig. 8 is a view in section taken on the line 8—8 of Fig. 7;

Fig. 9 is a fragmentary front elevation of a further modified form of reed embodying my invention, part being broken away to show the 55 ends of the dents;

Fig. 10 is a section taken on line 10—10 of Fig. 9;

Fig. 11 is a fragmentary front elevation of a still further modified form of reed embodying my invention, the upper left hand portion being 5 broken away to show the ends of the dents; and

Fig. 12 is a section taken on line 12—12 of Fig. 11.

It will, of course, be understood that the description and drawing herein contained are illustrative merely, and that various modifications and changes may be made in the structure disclosed without departing from the spirit of my invention.

Referring more particularly to the drawing, 15 15 designates one of the side bar members of the framework of the reed. A similar bar (not shown) may be used at the other side of the reed.

The dents 16 extend approximately the same length as the bars 15, and portions adjacent the 20 ends of the dents 16 extend between respective convolutions 17 of the spring coil 18. The thickness of the wire of this spring coil of course determines the lateral spacing or gauge of the dents.

In order to maintain the dents in spaced relationship with their edges in a common plane, strips 19 are employed. Each of the strips 19 has a face 20 conforming in shape to the internal portion of the coil 18 and one of these strips is interposed within the coil, at each side of the 30 dents 16. Each of the strips 19 has a flat face 21 in contact with the dents 16 and the side bar 15.

The dent ends 22 have spaces 23 therebetween, and these ends 22, the coils 18 and the strips 19 are held in predetermined position by soft metallic material 24 which may be solder or the like and which covers and surrounds these several parts and fills the interstices therebetween. The proper form and shape of the reed assembly is thus obtained and maintained.

40 In a reed of this character, as heretofore constructed, the strains in the dents are concentrated at the place of contact or bearing of the end portions 22 of the hard metal dents on the hard metal coil 18. The vibrations in the reed 45 aggravate the condition already obtaining, and fatigue of the metal of the dent is brought about. The life of the reed is consequently shortened.

I have found, however, that by providing solder in the dent spaces, as at 25, filling the portions 50 of said spaces adjacent the spring coils, an improved reed construction is obtained. This solder, in the preferred form of my invention is integral with the solder 24 and is extended for some distance in the dent spaces toward the other end 55

of the dent and beyond the place of contact of the dent ends 22 and the coil 18. I do not intend to limit myself, however to solder which is integral, since the solder may be applied in any desired manner. A reed with my improvement embodied therein overcomes the difficulties heretofore encountered. By extending the solder in this manner, the effect of the concentrated strains appears to be overcome. The solder seems to act in the same manner as a bearing or resilient cushion. The weight is not materially increased, and the solder used as aforesaid does not render the reed dents excessively stiff.

In Figs. 3, 4, 7 and 8, I have shown my invention applied to a form of reed with which a casing member 26 is employed on each side of the bar and dents. This casing may be united to the end portion of the reed by soft metal, such as solder. An external shape, as there shown, is rendered necessary by reason of the form of the reed slot in the lay as found in a number of looms. This casing member, as will be seen by reference to the drawing, may have a straight outer end portion 27, an intermediate curved portion 28, and 25 an inner straight portion 29. In applying my invention to this form of reed, the solder 25 is preferably extended and fills a portion of each dent space sufficiently to bring the solder some distance beyond the inner straight portion 29 of 30 the casing 26.

In Figs. 9 and 10 I have shown my invention applied to a somewhat different form of reed. Reeds of this type are intended for use with looms in which the lay has a slotted receiving opening 35 to which the end portion of the reed is complementary. It will be noted that in place of the casing shown in Figs. 3, 4, 7 and 8, the exterior of the end of the reed may be finished by securing thereto flat facing strips 36 having an outer plane 40 surface. The solder 25 is extended for some distance beyond the coil 18 toward the other end of the reed and fills a portion of each dent space adjoining each coil.

Figs. 11 and 12 show a still different form of 45 reed construction, in which two spring coils 18a and 18b are used in place of the single coil found in the other forms. These coils are spaced apart as shown at 31. The ends may be finished by securing thereto flat facing strips 32, having an 50 outer plane surface, or the ends may be finished in any other desired manner to provide such a surface. The solder 25 is extended for some distance beyond the second coil 18b in a reed of this character and thus fills a portion of each dent space adjoining each coil 18b.

It will therefore be seen that I have provided a novel reed construction which will overcome the objections heretofore encountered.

I claim:

- 60 1. A loom reed including dents, means for securing the dents in spaced relationship and soft metal in each of the dent spaces, this metal filling the portions of said dent spaces adjoining said securing means and extending interiorly beyond the securing means.
- 65 2. A loom reed including dents, means for securing the dents in spaced relationship filling the portions of each of said dent spaces adjoining said securing means and solder, extending interiorly beyond the securing means.
- 70 3. In a loom reed, a plurality of dents, means

at one end for securing the dents in spaced relationship and soft metal in the interstices between the dents and the securing means and also filling portions of each of said dent spaces beyond the securing means toward the other end of the reed. 5

4. In a loom reed, a plurality of dents, means at one end for securing the dents in spaced relationship and solder in the interstices between the dents and the securing means, said solder also filling the portions of each of said dent spaces 10 beyond the securing means toward the other end of the reed.

5. In a loom reed, a plurality of dents, a coil adjacent one end of the reed, the ends of the dents extending between successive convolutions 15 of the coil, means extending in the coil for holding the dents and coil in fixed relationship, and soft metal extending into the dent spaces and filling the portions of each of said dent spaces beyond the coil and toward the other end of 20 the reed.

6. In a loom reed, a plurality of dents, a coil adjacent one end of the reed having the ends of the dents extending between successive convolutions of the coil, means extending in the coil 25 and in contact with said dents for holding the dents and coil in fixed relationship, and soft metal in the interstices between the dents and the coil, said soft metal also filling the portions of each of the dent spaces beyond the coil and toward 30 the other end of the reed.

7. In a loom reed, a plurality of dents, a coil having the ends of the dents extending therethrough, strips for securing the dents and coil in fixed relationship, and soft metal in the interstices between the dents and the coil, said soft metal also filling the portions of each of the dent spaces beyond the coil toward the other end of 35 the reed.

8. In a loom reed, a plurality of dents, means 40 at one end of the reed for securing the dents in spaced relationship, a casing enclosing the securing means, and soft metal in the interstices between the dents and the securing means, said soft metal also filling the portions of each of the 45 dent spaces beyond the securing means toward the other end of the reed.

9. In a loom reed, a plurality of dents, means at one end of the reed for securing the dents in spaced relationship, a casing enclosing the securing means and soft metal filling the portions of each of the dent spaces beyond the securing means toward the other end of the reed. 50

10. In a loom reed, a plurality of dents, a coil for spacing the dents having portions of the dents 55 extending therethrough, facing strips mounted on the portions of the dents beyond the said coil, and soft metal filling the portions of each of the dent spaces at the side of the coil distant from the facing strips.

11. In a loom reed, a plurality of dents, a coil for spacing the dents having portions of the dents extending therethrough, facing strips mounted on the portions of the dents beyond the said coil, and soft metal in the interstices between the dents 65 and the coil, said soft metal also filling the portions of each of the dent spaces at the side of the coil distant from the facing strips.

CERTIFICATE OF CORRECTION.

Patent No. 1,997,560.

April 9, 1935.

JOHN JACOB KAUFMANN.

It is hereby certified that error appears in the printed specification of the above numbered patent requiring correction as follows: Page 2, first column, line 67, claim 2, after "relationship" insert the comma and words, and solder; ; and line 69, strike out the word and comma "solder ,"; and that the said Letters Patent should be read with these corrections therein that the same may conform to the record of the case in the Patent Office.

Signed and sealed this 14th day of May, A. D. 1935.

(Seal)
